Henry A. Lauer, Chicago, Ill.

Application October 31, 1946, Serial No. 134,397

Term of patent 7 years

(Cl. D54—2)

To all whom it may concern:

Be it known that I, Henry A. Lauer, a citizen of the United States, residing at Chicago, in the county of Cook and State of Illinois, have invented a new, original, and ornamental Design for a Sheet of Metal or Similar Flat Surface Material, of which the following is a specification, reference being had to the accompanying drawing, forming a part thereof.

The figure is a plan view of a sheet of metal or similar flat surface material, showing my new design.

I claim:

The ornamental design for a sheet of metal or similar flat surface material, substantially as shown.

HENRY A. LAUER.
